(57) **CLAIM**

The ornamental design for an accessory for cushioning, as shown and described.

DESCRIPTION

FIG. 1 is a front perspective view of an example of the accessory for cushioning;

FIG. 2 is a rear perspective view thereof;

FIG. 3 is another rear perspective view thereof;

FIG. 4 is a front view thereof;

FIG. 5 is a rear view thereof;

FIG. 6 is a first side view thereof;

FIG. 7 is a second side view thereof;

FIG. 8 is a top view thereof; and,

FIG. 9 is a bottom view thereof.

The broken lines shown in the drawings illustrate portions of the accessory for cushioning that form no part of the claimed design.
